UNITED STATES PATENT OFFICE.

GEORGE Y. BONUS, OF CHICAGO, ILLINOIS.

REGENERATIVE POWER SYSTEM.

1,297,069.

Specification of Letters Patent. Patented Mar. 11, 1919.

Application filed July 20, 1917. Serial No. 181,732.

To all whom it may concern:

Be it known that I, GEORGE Y. BONUS, citizen of the United States, residing at Chicago, Illinois, have invented certain new and useful Improvements in Regenerative Power Systems; and I do hereby declare the following to be a full, clear, and exact description of the invention, such as will enable others skilled in the art to which it appertains to make and use the same.

My invention relates to fuel-utilizing and power generating apparatus, and, when viewed in its most general aspects, aims to provide a series of coöperating and inter-related means for utilizing the energy stored in fuel more effectively than has heretofore been customary, and for saving valuable by-products which have hitherto wasted in connection with such apparatus. For these general purposes, my invention aims to provide a coöperating aggregation of elements having various novel features in themselves and arranged in a novel manner with respect to each other so as to attain these objects as hereafter described. Viewed more in detail, the purposes of my invention include the following objects, all of which may desirably be combined as hereafter set forth, but many of which are accomplished in such a way that they may also be utilized to advantage in other connections than in the particular combination here described. These objects are: to provide a simple and highly efficient digestion for manufacturing water gas from coal and steam, and one which will leave nitrogenous gases and the like available as valuable by-products; to utilize the exhaust steam from an engine for which the live steam is generated with the water gas as fuel, as one element in the manufacture of the water gas, and to utilize the heat of the flue of the boiler for warming the digester; to use a superheater disposed in the same boiler which raises the steam for the engine, for providing the high temperature steam needed for making the water gas; to combine water evaporating and steam regenerating units in a single and simple boiler construction, and to use the former unit for replenishing the supply of steam used from the other unit in the manufacture of the water gas; to utilize the exhaust steam from the boiler supply pump jointly with the exhaust steam from the high-pressure cylinder of the engine for actuating the piston in the low-pressure cylin-

der of the engine; to utilize the exhaust steam of the engine for preheating the air supplied for the grates of both the digester (or water gas manufacturing part of the plant) and the steam boiler; to regenerate a part of the exhaust steam of the engine by successively boosting its pressure and thereafter boosting its temperature, and to condense another portion of the exhaust steam by the cooling water from the pressure-booster so as to secure the water supply for the water evaporating or moisture replenishing portion of the boiler; to utilize part of the heat of the flue gases from the boiler for reheating some of the steam supplied to the digester; and to provide simple means for enabling steam to be raised in the said water evaporating portion of the boiler independent of the steam regenerating portion of the latter, for starting the system in operation. Still other objects will appear from the following specification and from the accompanying drawings, in which drawings, Figure 1 is a partially diagrammatic vertical section of apparatus embodying my system as a whole, as installed in a two story plant. (It is to be noted however, that while it has seemed advantageous to illustrate the apparatus as arranged on two floors and as spread out laterally so that the elements will not conceal each other, I do not wish to be limited to these or other details of the construction or arrangement herein disclosed, it being obvious that the same might be varied in many respects without departing from the spirit of my invention.)

Figs. 2 and 3 are enlarged views corresponding respectively to the left hand and right hand portions of the semi-diagrammatic vertical section of Fig. 1.

In effecting the purposes of my invention, I start with a suitable fuel, such as coal, fed into a bunker 1, in which bunker the coal is dried and to some extent warmed by chimney gases entering from a branch 2 of the chimney 3, each of the latter being controlled by dampers 4 and 5 as indicated in the drawings. From the bunker 1, the coal is admitted as needed into a hopper 6 at the top of the digester, and is kept from ignition in the upper part of the digester by a water jacket 7. Steam at a relatively high temperature (say 1500° F.) is fed into the digester near its top through a pipe 8 from a superheater 9 desirably located close

to the grate of the boiler, this steam being desirably part of the exhaust of the exhaust steam of the engine 10 of my equipment. The resulting water gas, for the manufacture of which oil is supplied through a pipe 11 from a suitable supply of oil (which may desirably be partly from an oil separator 12 interposed in the exhaust pipe 13 of the steam engine 10) is drawn off at a somewhat lower temperature (say 1200°) from the digester and passes through a pipe 14 to the grate of the boiler. At the same time certain gaseous byproducts (such as ammonia and other nitrogenous gases) are emitted through a pipe 15 near the top of the digester or generator, thereby enabling these valuable byproducts to be utilized. To save fuel in heating the digester to the required temperature, I preferably surround the latter by an air jacket forming part of the chimney connection for the boiler, so that the digester practically is disposed within the boiler flue and warmed by the otherwise wasted heat of the flue gases. I also desirably use these flue gases for reheating the steam supplied at the grate of the digester through a pipe 16, as by inserting a reheater 17 in a chamber forming a portion of the flue. For the boiler, I desirably employ a type having both water evaporating elements and steam regenerating elements, and with these elements so arranged that they can be operated independently of each other whenever this seems desirable. For example, in the embodiment of the drawings, the inclined tubular legs 18 form part of a water tube boiler which generates steam and supplies the latter from an upper drum 19 to the entrance drum 40 of the steam regenerating tubes 20 and 21. The steam is then forced by the compressor 22 through the tubes 20 and 21 to the high pressure steam drum 23 of the boiler, and passes from the latter drum through the supply pipe 24 to the high pressure cylinder 26 of the engine 10. When starting the system, this pipe 24 may be kept closed by the valve 25 until sufficient pressure has been generated within the drum 19 for initially actuating the engine and hence starting the compressor 22, the latter being driven by the engine 10 and being desirably a multi-stage turbo compressor. After being expansively utilized in both the high pressure cylinder 26 and the low pressure cylinder 27 of the engine, the exhaust steam passes through a pipe 28 into a semi-condenser 29, in which this steam passes around tubes 30 and is partly condensed by water from pipes 31. The water supplied for this purpose is desirably that used for cooling the compressor 22, and the mixture of the sprayed water with the steam condensed by it is taken to the pump 32 which replenishes the supply

of water for the water tube portion of the boiler. The non-condensed part of the steam passes over a partition 33 in the semi-condenser 29 to the compressor 22, and the latter raises its pressure to that desired for 70 actuating the piston in the high pressure cylinder of the engine; after which the pressure-raised steam is heated in the tubes 20 and 21 to the temperature normally corresponding to its pressure, thus completing 75 the steam regenerating cycle more fully described in my copending application filed March 23, 1917, as Serial No. 156,806.

As a further means both for cooling the exhaust steam of the engine and for utilizing the heat of the latter, I force air through the tubes 30 of the semi-condenser by means of a fan 34 and supply the resultant preheated air through the duct 35 to the grates of both the boiler and the digester or water gas producer. For the grate of the latter, I also desirably supply steam taken through a pipe 36 from that issuing from the semi-condenser, heating the same in the reheater 17 as already described. 90 However, for the steam supplied near the top of the water gas producer (where a higher temperature, such as 1500° F. is desirable), I preferably tap the exhaust of the engine by a pipe 37 leading to the superheater 9 which then supplies the superheated steam through the pipe 8.

As further measures of efficiency and economy, I also desirably combine the exhaust steam of the pump 32 with that from the 100 high pressure cylinder 26 of the engine and then use the combined exhaust for actuating the piston in the low pressure cylinder 27. So also, I preferably admit a small percentage of the chimney gases, to the water gas producer through an inlet 38, so as to profit by the carbon dioxid content of these gases, adjusting the inlet opening according to the gas conditions in the flue and the state of operation of the producer, a suitable 110 chimney draft being assured by a blower 39.

From the above, it will be evident that when my apparatus is once started, it can easily be operated continuously for utilizing 115 low grade coal with the usual efficiency obtainable by first producing water gas from the latter. By employing the steam regenerating system disclosed and claimed in my cited copending application, I reduce the amount of water needed for replenishing the boiler substantially to that consumed in the manufacture of the water gas, and as this quantity can readily be used to advantage in cooling the turbo-compressor (in doing which the water itself is somewhat warmed) I employ otherwise wasted heat for warming the water supply. While the desirability of clearness in the drawings has caused me to spread out various elements laterally of each other and above each 120 125 130

other it will also be obvious that they can easily be grouped compactly, thereby reducing the lengths of the pipe and flue connections. Consequently, I am able to practically eliminate the intermediate losses in temperature or pressure, and by thus utilizing the various heating and cooling effects as above described, I am able to obtain an unusually high output of engine power from a given quantity of coal even when the latter is of a relatively low grade. However, many of the novel features herein disclosed may also be used advantageously in plants employing only a part of the apparatus above described as coöperating, or in plants in which other elements are substituted for part of what I have described and pictured in this illustrative embodiment. Hence I do not wish to be limited to this particular combination, particularly since local conditions may often make alterations or modifications desirable as to one or more of the novel features here disclosed, which variations might easily be made without departing from the spirit of my invention.

I claim as my invention:

1. The combination with a steam-driven prime mover, of means for successively cooling the exhaust to a point above its condensing temperature, mechanically raising the pressure of the cooled exhaust, reheating the exhaust, and resupplying the same to the prime mover; a steam generator associated with the reheating means for maintaining the desired moisture content, and single means for heating the steam generator and supplying the thermal units for reheating the exhaust, in combination with a water gas producer for supplying fuel to the said single means; the exhaust-cooling means including an air supply for the gas producer and a water supply for the said steam generator.

2. In combination, means for using part

of a supply of steam expansively and non-condensingly and for using another part thereof expansively and condensingly; successively operating means for cooling the non-condensingly used exhaust, raising the pressure of the said exhaust, and reheating the pressure-raised exhaust to the temperature of the initial steam supply; means for evaporating water to produce steam corresponding to that which was used condensingly, and a water supply arranged for affording the said cooling and thereafter supplying water to the said evaporating means.

3. In combination, a producer for generating water-gas, a steam boiler heated by the burning of said gas, a common air supply for both the boiler and the producer, a power appliance utilizing steam from the boiler expansively, a condenser for the exhaust steam, and means associated with the condenser for utilizing a part of the heat of the exhaust steam in warming the said air supply.

4. In a power unit, a lower drum, a pair of upper drums connected thereto by tubes, a steam inlet for the first of the upper drums, means connecting the second upper drum with an engine or the like, mechanical means interposed between the exhaust of the engine and the said inlet for raising the pressure of the exhaust and forcing the latter through the said drums and tubes, and means for heating the pressure-raised exhaust during its passage through the drums and tubes to a temperature corresponding substantially to its pressure.

5. A power unit as per claim 4, in combination with means for supplying fresh steam to the first named drum to replenish losses in the system.

Signed at Chicago, July 16th, 1917.
